UNITED STATES PATENT OFFICE.

JAMES CAREW, OF LIVERPOOL, ENGLAND.

FURNACE FIRE-GRADE.

1,147,605.

Specification of Letters Patent. Patented July 20, 1915.

Application filed June 12, 1913. Serial No. 773,306.

To all whom it may concern:

Be it known that I, JAMES CAREW, subject of the King of Great Britain, residing in Liverpool, in the county of Lancaster, in the Kingdom of England, have invented 5 certain new and useful Improvements in Furnace Fire-Grates, of which the following is a specification.

The present invention relates to that kind 10 of furnace wherein the main fire grate is composed of fire bars having air conduits passing longitudinally through them, and wherein at the back of the main grate there is a separate or auxiliary grate of removable 15 sloping fire bars also having longitudinal air conduits corresponding to and forming continuations of those in the firebars of the main grate. In this kind of furnace, each sloping hollow bar has hitherto been hooked 20 at top on a back bearer, while its lower end was socketed on to a spigot on the corresponding hollow main bar, so that they were practically in a single length jointed together; in fact the heat of the furnace practically 25 welded the sloping bars to the main bars. Now according to the present invention, the jointing together of the hollow upwardly sloping bars, and the hollow main bars, is dispensed with, and my improvement is 30 characterized in that the lower ends of the hollow sloping bars and the adjacent ends of the hollow main bars are independently interlocked in position by a bearer, but without obstructing the passageway through 35 the bars, so that when any particular bar is burnt or worn, it can be removed and replaced without removing any of the other bars.

In the accompanying drawings, Figure 1 40 is a sectional side elevation illustrating the disposition of my invention in the furnace flue of a boiler; Fig. 2, a view looking at the front of the bridge with some of the bars removed; and Fig. 3 a plan view; Fig. 45 4 is a vertical sectional view partly broken away, showing a slight modification of the interlocking connection; and Fig. 5 is a horizontal sectional plan view of the form of device shown in Fig. 4, with part of the 50 bridge wall bars removed.

In these figures, A are the main firebars resting on the front end of the usual dead-plate B, and at the rear end on the rest C; D are the upwardly sloping bars resting or 55 hooked at top on the back bearer E, their lower ends resting on the rest C. This back

bearer E consists of a chair plate, being formed of an upstanding part E, the forward projecting flange of which forms the rest C. In Figs. 1, 2 and 3, this rest has cast 60 on it a vertical web with lateral flanges or beads G H at the top. The rear ends of the main bars A are so shaped as to fit against the web between the rest C and the flange G. The lower ends of the sloping bars D are 65 shaped to rest on the flanges G, H, and fit against the web between the rest C and the flange H, and are provided with a notch into which the flange H enters. Thus both sets of bars are interlocked with the rest C. In 70 Figs. 4 and 5, the web is affixed to the rest C, and has a flange G at the forward side.

In Figs. 4 and 5, the rest C carries a vertical web whose base flange F has spaced ribs F', so as to leave an air space N, which 75 forms an interstice, while at the top this vertical web has a flange G at the forward side. The rear ends of the main fire bars A are so shaped as to fit against the web, between the rest C and the flange G, so as to 80 interlock therewith. The lower ends of the sloping bars D have a cut away portion so that the forward part rests on the flange G, while the rearward part rests on the rest C in the space between the base flange F and a 85 stop bar I affixed to the rest C. Thus both sets of bars are interlocked with the rest C, so that the rear ends of the main bars A interlock with it the same as hereinbefore 90 described, but the rear of the web has no flange H, but there is instead a stop bar I affixed to the rest C. The lower ends of the sloping bars D are so shaped as to rest on the flange G, and between the web and the stop bar I. There are air conduits J passing 95 through the bars, these conduits J commencing at the underside of the main bar near the front end, and passing longitudinally through the bar to the other end and through the upsloping bars, so that air from below the firegrate can pass through the bars into the combustion chamber or smoke box to assist in producing more complete combustion and keep the bars cool, and the air is heated in its passage thus supplying 100 hotter air than can be obtained in the ordinary way. I am aware that the conduits through firebars have commenced at the front end and have opened endwise, and not at the under side. In this connection, 105 my improvement consists in making the conduits so as to commence at the under side

near the front end. To keep the conduits J through the bars clear, steam can be blown through the bars by means of a jet S. Ports K are made in the web so as to connect the 5 conduits J in one set of bars A with those in the other set D. The conduits J in the sloping bars D adjacent to the rest C are made tapering at L so as to receive the air current as it flows through the ports K. The tapering 10 holes extend to the bottom of the bars D in such manner that the web and flange G lie substantially in the mouth of the tapering hole. The air current issuing through the ports K enters the conduits in the sloping 15 bars, and is discharged at the top end of the sloping bars into the combustion chamber or smoke box. Thus the passage of air from the bars A to the bars D is facilitated, and the bars locked to the rest C cannot get 20 displaced, as when a pricker bar is used by the fireman, thus insuring that the conduits in the respective bars shall lie in line, and ash cannot penetrate between the adjacent ends of the bars. Besides the usual air 25 spaces P between the bars, small vertical air channels Q are provided between the bars D at the top and where they rest or hook in the back bearer E. Air entering the chamber R penetrates through these air 30 channels Q and discharges itself at the top, the bars D fitting the back bearer loosely so as to allow air to pass, the object being to prevent clinker accumulating on the top of the sloping bars. In cases where the 35 furnace tube T is corrugated, the bars at the side of the furnace are shaped at U to fit the corrugations.

It will be evident that by this invention, when all the bars are placed side by side in 40 position, the whole by reason of the up-standing bars form a hollow fire bridge with interstices in front. Any individual bar or all the bars can very readily be removed by simply raising them off the back bearer E, 45 or they can be easily replaced and the whole arrangement is of the simplest possible character.

I declare that what I claim is:—

1. In a firegrate, the combination of a rest 50 C having affixed to it a vertical web with lateral flange G, spaced ribs F¹, and stop

bar I, hollow main fire bars whose rear ends are so shaped as to come against the web between the rest and the flange G, hollow sloping fire bars at the back of the main bars 55 whose lower ends are so shaped as to rest on the flange G and come against the web between it and the stop bar I, and ports in the web to connect the conduits in the main bars with those in the sloping bars. 60

2. In a firegrate, the combination of a rest C having affixed to it a vertical web with ports therein, main fire bars whose rear ends are so shaped as to interlock with said rest at one side, sloping fire bars whose 65 lower ends are adapted to interlock with said rest at the other side, and longitudinal air passages through the fire bars coinciding with the ports in the web, those in the sloping bars being splayed or tapered at the 70 lower end, so as to receive the air current issuing through the ports.

3. In a firegrate, the combination of a rest C having affixed to it a vertical web with ports therein, main fire bars whose rear ends 75 are so shaped as to interlock with the said rest at one side, sloping bars adapted to interlock with the said rest at the other side, longitudinal air passages through the bars coinciding with the ports in the web, the 80 said air passages commencing at the under side of the main bars near the front end.

4. In a firegrate, the combination of a rest C having affixed to it a vertical web with ports therein, a back bearer, main fire bars 85 whose rear ends are so shaped as to interlock with the said rest at one side, sloping bars hooked at top on to the back bearer and adapted to interlock with the said rest at their lower end, longitudinal air passages 90 through the bars coinciding with the ports in the web, and air channels Q between the hollow sloping bars at the top end, where they hook on the top of the back bearer.

In witness whereof, I have hereunto 95 signed my name this 4 day of June 1913, in the presence of two subscribing witnesses.

JAMES CAREW.
